Primary Examiner — W. A. Teddy Falloway

(74) Attorney, Agent, or Firm — Sanchelima & Associates, P.A.; Christian Sanchelima; Jesus Sanchelima

(57) CLAIM

The ornamental design for an egg container, as shown and described.

DESCRIPTION

FIG. 1 is an isometric top view of an egg container showing my new design;

FIG. 2 is an isometric bottom view thereof;

FIG. 3 is a front view thereof;

FIG. 4 is a rear side view thereof;

FIG. 5 is a left side view thereof;

FIG. 6 is a right view thereof;

FIG. 7 is a top view thereof; and,

FIG. 8 is a bottom view thereof showing my design.

1 Claim, 8 Drawing Sheets(56)
